UNITED STATES PATENT OFFICE.

BEDFORD T. KAVANAUGH, OF CHICAGO, ILLINOIS.

SASH-FASTENER AND BURGLAR-ALARM.

SPECIFICATION forming part of Letters Patent No. 777,344, dated December 13, 1904.

Application filed February 18, 1904. Serial No. 194,213. (No model.)

To all whom it may concern:

Be it known that I, BEDFORD T. KAVANAUGH, a citizen of the United States, residing at Chicago, in the county of Cook and State of Illinois, have invented a new and useful Improvement in Sash-Fasteners and Burglar-Alarms, of which the following is a specification.

My object is to provide an improved sash-fastener which will operate to lock a vertically-sliding sash in closed or partly-opened positions and also to provide in combination therewith improved electric alarm mechanism which will be sounded when it is attempted to move the sash from the outside.

Referring to the drawings, Figure 1 is a broken vertical section on line 1 in Fig. 2 through the upper and lower sashes of a window and showing my improvements in section; Figs. 2 and 3, broken plan sections taken on lines 2 and 3, respectively, in Fig. 1; Fig. 3^a, a plan section of a plunger-latch casing; Fig. 4, a broken elevation of the stile at one side of the upper sash provided with a socket-plate forming one of the details of my improved construction; Fig. 5, an edge view of the stile shown in Fig. 4, and Fig. 6 a face view of the sash-casing against which the surface of the stile shown in Fig. 5 slides.

A is an upper sash, and B a lower sash. Countersunk in a groove in one of the side rails of the sash A is a metal contact-plate *a*, having openings fitted with washers *b*, of insulating material.

C is a plate fastened in place by screws *c* passing through the washers *b* into the sash-stile and spaced from the plate *a* by the washers *b*, whereby the plates C *a* are spaced and insulated from each other. The plate *a* has a lug *a'* at its upper end, and on the plate C is a lug C'. The lugs *a'* C' are connected, by means of wires *a'* C², respectively, with parallel spring contact-plates *a'* C², which are fastened at one end upon the edge of the sash-stile. In the plate C is a series of sockets *d*, presenting upper abrupt shoulders *d'* and lower inclined shoulders *d''*. At the upper end of each socket *d* is an opening *d'* through to the back of the plate. Fastened against the back of the plate at each socket is a leaf-spring *e*, projecting at its free end through the open-

ing *d'* to extend in an upward and outward inclined direction and held normally along its body portion against the back of the plate C out of contact with the plate *a*.

On the lower sash B is a spring plunger-latch D, having a casing *f* fastened upon the sash. In the casing is a sleeve *g*, having a projecting head or handle portion *g'* and formed at its inner end with a flange *g''*. Secured in the outer end of the casing is a collar *f'*, and a spring *g'* around the sleeve and confined between the flange *g''* and collar *f'* tends normally to press the flanged end *g''* against the inner end of the casing-chamber. Extending through the sleeve is the shank or stem *h* of the plunger-latch, having the engaging end *h'*. A nut *h''* on the outer end of the stem *h* holds the latch against independent longitudinal movement in the sleeve. The engaging end portion of the latch presents a beveled corner *h*³ at its under side and an abrupt shoulder *h*⁴ on its upper side. Fastened to the plate *a*, at the lower end thereof, is a spring *e'*, normally out of contact with the plate C. The plates C² *a'* on the window-sash press at all times when the sash is closed or partly opened in contact with spring plates or strips *i* *i'* in the window-casing E. The plates *i* *i'* are insulated from each other and are connected by wires *i''* with a battery *i''*, and as the spring-strips C² *a'* bear always in sliding contact with the strips *i* *i'* the plates C *a* form the terminals of the electric circuit. Interposed in the circuit is an electric bell or alarm device *i*.

The sleeve *g* of the latch device is provided at its end with a laterally-projecting pin *g*⁴, movable in a slot *f''* in the casing *f*, which slot has lateral enlargements at opposite ends presenting shoulders *f*³ *f*⁴. The spring *g'* tends normally to hold the latch with its head *h'* in the extended position shown; but by drawing upon the handle *g'* the head may be withdrawn into the casing and held there by turning the sleeve *g* to cause the pin *g*⁴ to engage the shoulder *f*⁴. The latch may be locked in its extended position by turning the pin *g*⁴ over the shoulder *f*³. When the window is closed, the latch when released extends just beneath the spring *e'*. Any attempt to raise the lower sash or lower the upper sash

will cause the latch to press the spring e' against the lower end of the plate C, thereby closing the circuit and sounding the alarm. When the latch is withdrawn and locked in the withdrawn position, the upper and lower sashes may be freely raised and lowered without the latch entering any of the sockets. When the latch is released, it will enter any one of the sockets d with which it may register, in which position it will prevent further opening of the window, and, if desired, it may be locked against withdrawal by turning the pin g^2 behind the shoulder f^3 to prevent closing of the window. When the latch is in one of the sockets, any attempt to raise the lower sash or lower the upper sash without first withdrawing the latch will cause the latter to engage the inclined surface of the spring e in the respective socket and press the same against the plate a , closing the circuit and sounding the alarm. The latch can only move a spring e far enough to contact with the plate a when it engages the upper end of the spring, as when the latch is forced against the shoulder d' . While the latch is in the unlocked extended position the window may be closed by exerting sufficient force in the closing operation to cause the inclined shoulders d^2 to retract the latch, and if the window is closed quickly the latch would jump over the ends of the springs, and thus would not sound the alarm.

The window-fastening mechanism described forms a particularly strong and desirable means for locking the window either when closed or opened a short distance for ventilation, and the electric-alarm feature forms a certain and positive means for sounding an alarm in case any attempt is made to move either of the sashes from the outside.

While I prefer to construct my improvements throughout as shown and described, they may be variously modified in the matter of details of construction without departing from the spirit of my invention as defined by the claims.

What I claim as new, and desire to secure by Letters Patent, is—

1. The combination with upper and lower vertically-sliding window-sashes, of a spring

plunger-latch on the lower sash, an electric-alarm circuit, a plate on the upper sash forming one of the terminals of said circuit and having a vertical series of sockets in the path of said plunger, a contact-plate forming the other terminal of said circuit and extending across the bases of all the said sockets, and inclined contact-springs in the sockets movable by engagement therewith of the latch to engage the contact-plate and sound the alarm, substantially as and for the purpose set forth. 55

2. The combination with upper and lower vertically-sliding window-sashes, of a spring plunger-latch on the lower sash, an electric-alarm circuit, a plate on the upper sash forming one of the terminals of said circuit and having a vertical series of sockets extending through it in the path of the latch to be engaged thereby, each socket presenting an abrupt upper shoulder, forming a stop, and an inclined lower shoulder, a contact-plate, forming the other terminal of the circuit, behind and parallel with said socket-plate and insulated therefrom, and inclined springs in said sockets movable under engagement therewith of the latch to press against said contact-plate, substantially as and for the purpose set forth. 65

3. The combination with upper and lower vertically-sliding window-sashes, of a spring plunger-latch on the lower sash, an electric-alarm circuit, a plate on the upper sash forming one of the terminals of said circuit and having a vertical series of sockets extending through it in the path of the latch to be engaged thereby, each socket presenting an abrupt upper shoulder forming a stop, and an inclined lower shoulder, a contact-plate forming the other terminal of the circuit behind and parallel with said socketed plate and insulated therefrom, inclined springs in said sockets, 85 and a spring on said contact-plate extending beneath said socketed plate, all said springs being in the path of said plunger to be actuated thereby to sound the alarm, substantially as and for the purpose set forth. 90

BEDFORD T. KAVANAUGH.
